BRIDLE BIT

Eugene L. Ulrich, Pendleton, Oreg.

Application January 9, 1946, Serial No. 640,020

3 Claims. (Cl. 54—6)

1

This invention relates generally to equestrian equipment and particularly to a bridle bit.

The main object of this invention is to provide an exceedingly simple form of bit, in which the head stall is buttoned to the bit in the same manner as a spur strap is buttoned to a spur, thereby eliminating the head stall pinch entirely, and leaves the mouth piece in the same position in the horse's mouth at all times.

The second object is to employ a heavy round bar just in front of the rein rings, causing the bit to have a swinging or shock absorbing motion and thereby giving the bit a much better balance.

The third object is to render unnecessary a steady pulling and jerking of the reins, requiring merely a twitch of the reins to cause the lower part of the bit to swing backwardly towards the horse's body, bringing the curb strap in contact with the horse's chin. The curb strap immediately falls away and falls clear of the horse's chin unless he is ridden with a tight rein. Therefore the object is to so construct the bit, that a straight mouth piece can be employed in order to provide the shock absorbing motion, and also to eliminate fretting, worrying or champing at the bit.

The fourth object is to expedite the leading of saddle horses and to provide a bit which will not cause the horse to throw his nose up to get away from the pressure on his tongue, which is commonly the case with mouth pieces which are not straight.

The fifth object is to employ a head stall which does not interfere with the top of the bit (touch the curb strap) as the shape of the horse's head spreads the head stall away from the horse's cheeks.

The sixth object is to enable the rider, as he so wishes, to apply more pressure to the horse's chin, and to relieve the pressure on the tongue and bars. He may do this by putting a nose band underneath the head stall. In other words, it may be converted into a hackamore bit.

These and other objects are accomplished in the manner set forth in the following specifications, as illustrated in the accompanying drawings, in which:

Fig. 1 is a side elevation, showing the device applied to a horse's head.

Fig. 2 is a front elevation taken along the line 2—2 in Fig. 1.

Fig. 3 is a section taken along the line 3—3 in Fig. 1.

2

Fig. 4 is a side elevation, showing the position of the bit when a horse is grazing.

Fig. 5 is a view, showing the position of the bit when the horse is being lead.

Similar numbers of reference refer to the same or similar parts throughout the several views.

Referring in detail to the drawing, there is shown a common form of cheek piece 10, across the upper end of which is placed the usual front 10 of a head strap 11, which also supports the throat latch.

The lower ends of the cheek straps 10 are provided with slots 13 to receive the reduced ends 14 of the bit core, which is preferably covered 15 by means of a copper tubing 16, which lies within the bit arms 17. On the outer ends of each reduced end 14, is mounted a button 18, which is preferably riveted thereon.

Disposed across the ends 19 of the bit arms 17, 20 is a curved bar 20, provided with a ring 21, to which is attached the snap 22 secured on the end of the strap 23, whose upper end is attached to the throat latch 12, while its lower end passes above the curb straps 25, which are attached to the curb rings 26 of the bit. The usual reins 27 are attached to the rein rings 28.

It can be seen from the foregoing, that in the construction herein disclosed, there is provided a bit, having a wide range of uses, with the utmost 30 amount of comfort for the horse wearing same. It can be seen that the bit is a free swinging bit, and that the rider has, within his power, the opportunity to adapt the bit to its best use, whether it be riding or leading the animal or 35 permitting it to graze.

Attention is especially drawn to the fact that the member 16 is preferably made of copper or bronze, as this metal is preferred by the animal.

It will be noted that between the ends of the 40 strap 23, is secured a ring 29, to which the snap 22 may be attached if it is passed around the curb strap 25, the purpose of which is readily discernable by inspection of Figs. 4 and 5.

I am aware that many forms of bits have been 45 constructed in the past. It is therefore, not my intention to cover such devices broadly, but I do intend to cover all such forms and modifications of the invention that fall fairly within the appended claims.

50 I claim:

1. A bridle having in combination a pair of cheek straps, a straight bit mounted across the lower end of said straps, bit arms depending from the ends of said bit, a cross bar constituting 55 a counter-weight disposed in front of the lower

ends of said bit arms, a throat latch attached to said cheek straps, and a strap secured to said cross bar between the lower ends of said bit arms and the under side of said throat latch adapted to limit the swinging movement thereof.

2. A bridle of the class described, consisting of a pair of cheek straps having a head strap across the upper end thereof and having a throat latch secured to said head strap, a straight bit having a pair of depending bit arms, one at each end thereof, reins attached to the lower ends of said bit arms, a counter-weight attached to said bit arms in front of said rein fastening, and a strap between said counter-weight and throat latch adapted to limit the swinging movement of said counter-weight.

3. A bridle having in combination a straight bit

core, having a tubular bronze covering, a pair of bit arms having a counter-weight rigidly joined to their outer ends and having their opposite ends suspended from said bit core, and cheek straps having slits formed therein engaging said core outside of said bit arms.
